UNITED STATES PATENT OFFICE.

WILLIAM T. CARTER, OF CHICAGO, ILLINOIS.

ICE-WEIGHING TONGS.

SPECIFICATION forming part of Letters Patent No. 626,052, dated May 30, 1899.

Application filed September 26, 1898. Serial No. 691,898. (No model.)

To all whom it may concern:

Be it known that I, WILLIAM T. CARTER, a citizen of the United States, residing at Chicago, in the county of Cook and State of Illinois, have invented a new and useful Ice-Weighing Tongs, of which the following is a specification.

My invention relates to improvements in ice-weighing tongs; and the object of my invention is to furnish a device in which the ice-tongs used in the delivery of ice from house to house or otherwise may at the option of the operator be used to weigh or show the weight of the respective pieces of ice. I attain this object by the use of the mechanism shown in the accompanying drawings, in which—

Figure 1 is an elevation showing the ice-tongs and scales. Fig. 2 is a broken section showing the tongs and scales and detachable handle. Fig. 3 is another view showing the tongs, scales, and detachable handle. Fig. 4 is a vertical section of Fig. 3, showing the scales extended in weighing and the attachment of the scales to the tongs and detachable handle. Fig. 5 is a modification showing another adjustment of the detachable handle.

Similar letters refer to similar parts throughout the several views.

In the drawings, A represents the tongs proper, having limbs or half-tongs a and B. The half-tongs B have a handle B', detachable, for the purpose hereinafter described, and a head C, having a flat top and sloping lateral walls, upon which the saddle b is designed to rest.

D is a vise operated by the thumb-screw E, having right and left threads e' for the purpose of moving the jaws d d equally toward each other to clamp the saddle b on the head C, thus adapting the tongs for handling the ice without the use of the scales.

K is the scale-frame, movably suspended from pins or projections l of the head C. The said projections l have a further extension l', which plays vertically in channels h h in the cylinders g g, inclosing the springs H H of the scales G. Attached to the bottom and at either side of the scale-frame K are two springs H H, sufficiently powerful to support

the weight of the ice designed to be handled, which springs are also attached to the base of the handle B', as shown in Figs. 3 and 4. Thus the scales G are suspended or attached at two points—namely, at the handle B' and the head C—and when the tongs are operating in carrying, holding, or handling ice the weight is on the tongs only and the scales are not in use.

A dial-plate I is placed or marked on each cylinder g g, as shown in Fig. 3, or preferably opposite each other on the cylinders to allow the registration of the weight of the ice, and portions J J of the scale-frame K are brought around the cylinders to act as index or registering points and register the weight on the dials when the scales are in operation.

In operating my device the ice-tongs are used in the customary way in the handling of ice until it is desired to weigh the ice in the tongs, when the operator turns the thumb-screw E, thus opening the jaws d d of the vise D and releasing the saddle b of the handle B', thus disconnecting the said handle from the head C. The effect of this disconnection is to throw the weight of the ice upon the scales, which are now suspended only by the tops of the springs from the base of the handle B', as shown at m of Fig. 4. The weight of the ice extends the springs and carries downward the dial-points J J along the dial-faces i, upon which they register the proper weight of the ice. In Fig. 4 the points J J on the sides of the cylinders are the registering or dial points shown as carried down from their position, as shown in Fig. 3, by the weight of the ice. After weighing, the ice may be deposited, thus relieving the tension on the springs, which thereupon return the head C and its connections to the disconnected handle B'. In its return the head C is guided back into its place by the channels h h, in which its projections l' l' are adapted to reciprocate, all as shown in Fig. 4. When the saddle b is again seated on the top of the head C, the thumb-screw E is turned and the vise D is closed upon the saddle, thus securing the handle in place and adjusting the tongs anew for the ordinary handling of ice.

My scales being attached to one blade of the tongs, close to the handle, lie on both sides of

said blade. When the tongs are distended to grasp a large piece of ice, the blade, with the scales, lies over at a wide angle from the perpendicular, and when by the disconnection of the handle for weighing the weight is thrown on the scales it swings by gravity under the handle to which the scales are attached, the scales become perpendicular, and in this position the weighing is done. When the weight is then released, the coils of the spring collapse and move the tongs unerringly and automatically backward into connection again with the handle, where it may be fastened ready to operate as tongs only.

15 The use of the double scales is valuable to secure equilibrium of the device and also to sustain a heavier weight with shorter tension than single scales would do and to quickly and unerringly restore the head C to its socket or saddle b. When the tension is released, the two springs attached at the bottom of the scale-frame K contract and draw the head C, with its attachments and its projections l' l', evenly along the channeled ways h h in the cylinders g g until the head C is socketed in the saddle b and the springs have retired into and are covered by the cylinders g g.

In lieu of the fastening D any other fastening connecting the head C and the handle B' may be used which will effect similar results.

30 What I claim as my invention, and desire to secure by Letters Patent, is—

1. The combination of an ice-tongs with duplex or double weighing-scales to secure equilibrium and just poise and balance of the device, substantially as described and shown.

2. In an ice-tongs spring-scales for weighing ice, said scales being provided with double or duplex spring or coil, one spring being

located on each side of the tongs-arms, substantially as described and shown.

3. In an ice-tongs, spring-scales for weighing ice provided with a plurality of coils to shorten the step or expansion of the scales, substantially as described and shown.

4. In an ice-weighing tongs the blade, a, the blade, B, the handle, B', having saddle, b, the vise, D, to clamp the saddle and scales, G, substantially as described and shown.

5. In an ice-tongs the combination of the frame or scale support and duplex scales mounted on said frame, substantially as described and shown.

6. In an ice-weighing tongs, the combination of a handle optionally detachable from a grapple, a grapple constructed to reciprocate from said handle to the weighing-point between a plurality of spring-coils, a plurality of spring-coils, one on each of two sides of the grapple, to secure automatic return of the head to the handle, and a frame or means of sustaining said coils in said relation and in connection meditately or immediately with the handle, substantially as described and shown.

7. In an ice-weighing tongs, the combination of a grapple having a head adapted to reciprocate between two cylinders, slotted or channeled cylinders adapted to guide the reciprocating head, and springs within the cylinders adapted to exert a pressure on or move the head and grapple substantially as described and shown.

In testimony whereof I affix my signature in presence of two witnesses.

WILLIAM T. CARTER.
